(57) **CLAIM**

The ornamental design for a deposition ring for a physical vapor deposition chamber, as shown and described.

DESCRIPTION

FIG. 1 is a perspective view of a deposition ring for a physical vapor deposition chamber, according to the novel design.

FIG. 2 is a top plan view thereof.

FIG. 3 is a bottom plan view thereof.

FIG. 4 is a front elevation view thereof.

FIG. 5 is a back elevation view thereof.

FIG. 6 is a left side elevation view thereof.

FIG. 7 is a right side elevation view thereof, and,

FIG. 8 is a cross-sectional view taken along line 8-8 in FIG. 2.

The dashed lines in FIGS. 1-8 represent unclaimed environment forming no part of the claimed design.

1 Claim, 4 Drawing Sheets
